UNITED STATES PATENT OFFICE.

JOSEPH B. JOHNSON, OF LOS ANGELES, CALIFORNIA.

VENDING MACHINE.

Application filed January 19, 1926. Serial No. 82,190.

My invention is a vending machine, adapted to vend sheets of paper and in particular paper for covering toilet seats.

An object of my invention is the provision of a vending machine operated by a crank, in which the insertion of a coin causes the crank to operate a drum, the drum unwinding a paper from a reel or roll and dispensing one sheet for each revolution of the crank.

A further object of my invention is to cause a coin to be an active element in transferring a driving force from the crank to the drum and a reciprocating device adapted to eject the coin from the coin slot and to take the place of the coin in transmitting the driving force from the crank to the drum.

A further object of my invention is to form a drum with a projection on its surface adapted to fit a cut out section of the paper and to feed same.

In the construction of my invention I mount a drum in a cabinet structure, preferably above a reel or roll of paper, the paper having cut-out portions and preferably having side notches and perforations to allow severance into sections. The drum has a projection on the surface adapted to fit in the cut-out portion of the paper and thereby positively feed the paper. A ratchet having a single tooth is mounted on the ends of the drum shaft and a weighted lever having a pawl tooth is pivotally mounted with one end of the lever adapted to rest on the free end of the paper, the lever being lifted by actuation of the drum allowing the paper to be dispensed and then dropping to hold the free end again.

In my coin controlled mechanism I mount a crank loosely on the end of the drum shaft. This crank has an arm with an offset section, the offset portion fitting in a transverse groove in a coin slot. The coin slot is formed in a hollow radial arm designated the ejector arm, keyed or otherwise secured to the crank shaft. An ejector is mounted in this arm spring pressed into its innermost position. When a coin is inserted in the coin chute and rests against the upper end of the ejector in the ejector arm, and on turning the crank, the projection on the arm engages the coin and transmits motion to the ejector arm and thereby turns the shaft and the drum. A stationary cam operates on the ejector in the ejector arm and

thrusts the coin out of the coin slot, the ejector replacing the coin in transmitting the turning force. After a complete sheet has been vended the crank may be turned in any direction but cannot vend another sheet until another coin is inserted.

My invention will be more readily understood from the following description and drawings, in which:

Fig. 1 is an exterior perspective view of a sheet paper vending machine, showing it in its normal position with the free end of the paper completely inside the delivery slot.

Fig. 2 is an outside side elevation.

Fig. 3 is a front elevation of the crank end.

Fig. 4 is a vertical longitudinal section as if taken on the line 4—4 of Fig. 3.

Fig. 5 is a vertical transverse section as if taken on the line 5—5 of Fig. 4.

Fig. 6 is a vertical transverse section of Fig. 4, on the line 6—6 in the direction of the arrows, showing the cam action.

Fig. 7 is an enlarged vertical transverse section on the line 7—7 of Fig. 4, in the direction of the arrows, indicating the coin slot operating mechanism.

Fig. 8 is a vertical longitudinal detail taken on the line 8—8 of Fig. 7, showing the ejector arm, the coin slot and the operative connection between the crank and the ejector arm.

Fig. 9 is a partial plan of the drum with the cover of the cabinet partly broken away.

Fig. 10 is a sketch showing a type of paper which may be vended by my machine.

My machine as to its exterior construction is particularly shown in Figs. 1, 2 and 3 and comprises a vending cabinet designated generally by the numeral 1, having a front end 2, a rear end 3, a front wall 4 and a rear wall 5. A hinged cover 6 forms the upper portion of the cabinet and a paper delivery slot 7 is formed at the junction surfaces of the cover and of the front wall 4. The front wall is provided with a cover plate which is removable to allow insertion of the reel or roll of paper.

The coin controlling mechanism is housed in a casing 9 secured to the front end of the cabinet and has a coin aperture 10 at its upper end and a coin receiving box 11 at the base thereof. A drum shaft 12 is journaled in the end walls of the cabinet as hereunder described, projecting through the

casing 9 and having a crank 13 thereon with a handle 14.

The reel or roll 15 shown particularly in Figs. 3, 4 and 5 is journaled in open topped bearings 16 and has the paper 17 wound thereon in the form of an ordinary roll.

The vending drum designated generally by the numeral 18 is shown particularly in Figs. 4, 5 and 9 and comprises a substantially cylindrical structure 19 mounted on discs 20, these discs being keyed or otherwise secured to the shaft 12. This shaft is mounted in journals 21 and 22 secured to the outside of the front and rear ends 2 and 3. The drum has a projection 23 adapted to fit in the cut-out portions of the paper as hereunder mentioned. A series of prongs 24 secured to the drum are also adapted to engage the paper at either the perforations as hereunder mentioned or to form perforations which allow easy tearing.

The means for controlling the vending of the paper is substantially as follows, being shown particularly in Figs. 4, 5 and 9:

25 An idler 25 is journaled in the cabinet in any suitable manner, the web 26 of the paper passing thereover. Pressure rolls 27 mounted on arms 28 pivotally mounted on a cross bar 29 are normally pressed against the 30 vending drum by means of springs 30.

35 Circular ratchets 31 and 32 are attached to the front and rear ends of the cabinet surrounding the shaft and each has a single notch 33. These notches engage a pawl tooth 34 of the weighted arms 35 carrying a transverse weight 36 at their outer end, the arms being pivotally mounted on the rod 29 or otherwise suitably supported. The delivery slot 7 has an apron 37 on which the weight 36 rests, holding the end of the web on the apron inside of the cabinet as indicated in Fig. 5 after a sheet of paper has been torn therefrom.

The operation of the vending drum is substantially as follows:

When the shaft is turned on account of the projection 23 fitting in the cut-out portion 38, of the sheet 39, forming part of the web 26 as shown in Fig. 10, the paper is fed 50 out of the delivery slot, the rotation of the drum being in the direction of the arrow 40 of Fig. 5. The web of paper is preferably formed with a series of perforations 41 and notches 42, the prongs 24 engaging the paper 55 at the perforations or if unperforated paper is used these prongs will form cuts allowing ready tearing of the paper. As the paper is forced out of the delivery slot it may be grasped by the purchaser and when the drum 60 has come to rest as hereunder mentioned, the sheet of paper may be torn at the perforations.

The coin controlling mechanism is substantially as described, being illustrated particularly in Figs. 4, 6, 7 and 8. The crank

13 has a hub 43 loosely mounted on the shaft 12 and held thereon by a nut 44. An arm 45 extends radially from the hub inside of the wall 46 of the casing 9, enclosing the coin mechanism, this arm having an inward projection 47. A block 48 is keyed or otherwise secured to the shaft 12, having a rotating seat with the journal 22 as indicated by the numeral 49; these features being shown in detail in Fig. 8.

A radial hollow ejector arm 50 extends outwardly from the block 48 and at its outer end has a coin slot 51. A transverse opening or slot 52 extends through the ejector arm and forms an opening across the coin slot. 80 An ejector 53 is mounted in the hollow space 54 of the ejector arm and has a base 55 adapted to rest on the block 48. An offset abutment 56 extends laterally from the ejector. This ejector has a stem section 57 adapted to fit in the coin slot and to slide therein. A compression spring 58 is positioned between the abutment 56 and the outer end 59 of the ejector arm and normally holds the ejector inwardly.

90 A cam 60 is attached to the outer end 2 of the cabinet, this cam being spiraled, having its inner end 61 close in to the block 48 as indicated in Figs. 7 and 8 and its outer end 62 situated a sufficient distance so that when the ejector arm rotates the stem section 57 of the ejector is forced outwardly in the coin slot across the transverse slot 52.

In order to hold the crank in its upper position when stationary, a spring pressed ball and socket device 63 co-acting between the crank and the wall 46 is secured thereto, the socket being positioned to engage the ball and hold the crank in the desired upright position.

The operation of my coin controlled mechanism is substantially as follows:

When the crank is in the uppermost position or hanging downwardly, or in any other position except when the projection 47 is directly in the coin slot, a coin may be inserted therein and rests on the upper end of the stem portion of the ejector. When the handle is turned in the proper direction, the projection 47 engages the coin and thus turns the hollow ejector arm in the direction of the arrow 64 of Fig. 7, by transmitting the pressure to the arm, thence to the block 48 which is keyed to the shaft 12. This action rotates the shaft and hence the drum, the drum functioning as above described.

In this action the abutment 56 rides on the outside surface of the cam 60 and gradually thrusts the coin outwardly of the coin chute until the ejector arm is in the reverse position, that is, extending downwardly when the coin is completely ejected. At this state of the movement the stem section 57 of the ejector takes the place of the coin across the transverse slot 52 and as the pro-

jection 47 bears thereagainst the ejector arm and the mechanism to which it is connected rotates to the uppermost position. When the abutment is free of the cam at the upper end 5 62 the spring 58 immediately thrusts the ejector downwardly, thus preventing any back movement and removing the stem portion from in front of the projection 47. Therefore the crank is free to rotate, the 10 projection passing freely through the transverse slot 52 but without operating any of the mechanism. The ball and socket spring device is only inserted for a matter of convenience as the crank can be left hanging 15 downwardly if desired.

It will be obvious from the above description that the vending mechanism may be considerably changed to vend different paper articles or lengths of paper and that the 20 coin controlled mechanism may also be considerably changed to suit different types of mechanism operated thereby. Such changes in the general construction and specific details will be within the spirit of my invention as set forth in the description, drawings and claims.

Having described my invention, what I claim is:

1. A vending machine comprising in combination a drum, means to support sheet material to be vended by the drum, means on the drum to engage sheet material, a rotatable shaft forming a mounting for the drum, a coin controlled mechanism mounted 30 on the shaft, a crank loosely rotatable on the shaft, the crank having a projection rigidly connected therewith, the projection being adapted to engage a coin in the coin controlled mechanism and thereby transmit a turning motion to the coin controlled 35 mechanism and hence to the drum, the slideable element forming part of the coin controlled mechanism, a cam to slide said element, the sliding of the said element being 40 adapted to eject a coin and the said sliding element forming a connection with the said projection.

2. A coin controlled vending machine comprising in combination a shaft, a crank 45 loosely rotatable thereon, a projection rigidly connected to said crank, an arm having a coin slot rigidly connected to the shaft, an opening through the arm to receive the said projection, a slideable element to hold

a coin in the said opening after insertion 55 in the slot, whereby the projection may engage the coin and transmit rotary motion through the arm to the shaft.

3. A coin controlled vending machine comprising in combination a rotatable shaft, a 60 hollow ejector arm rigidly mounted thereon, the ejector arm having a coin slot therein with a transverse opening across the slot, an ejector having a stem slidably mounted in the coin slot, a crank having a projection 65 rigidly connected therewith, the projection adapted to extend into the said opening and to engage a coin in the coin slot resting on the said stem, whereby rotary motion of the crank is transmitted through the coin to the 70 ejector arm and hence to the shaft.

4. A coin controlled vending machine as claimed in claim 3, having in addition a stationary spiral cam positioned to engage the 75 said ejector, the rotation of the shaft forcing the said stem across the opening in the coin slot, thereby displacing the coin and the said projection being adapted to bear against the said stem and transmit a turning motion 80 to the shaft.

5. A coin controlled vending machine comprising in combination a rotary shaft, a hollow ejector arm rigidly connected therewith, said arm having a radial coin slot and a transverse opening across the slot, an ejector 85 having a stem slidably mounted in the ejector arm, a spring tensioned to thrust the ejector arm towards the shaft, the stem extending into the coin slot forming a rest 90 for a coin inserted therein, a crank loosely rotatable on the shaft, an arm rigidly connected to the crank having a projection, the projection being adapted to register with the opening in the ejector arm and to engage a coin resting on the said stem, whereby 95 rotary motion of the shaft is communicated through the coin to the ejector arm and hence to the shaft.

6. A coin controlled vending machine as claimed in claim 5, having in addition a stationary spiral cam, the ejector bearing on said cam, whereby the rotation of the shaft forces the stem of the ejector into the coin slot thereby ejecting the coin, the said stem 100 engaging the said projection.

In testimony whereof I have signed my name to this specification.

JOSEPH B. JOHNSON.
